UNITED STATES PATENT OFFICE.

HENRY L. SMITH, OF WATERBURY, CONNECTICUT, ASSIGNOR TO THE E. J. MANVILLE MACHINE COMPANY, OF WATERBURY, CONNECTICUT, A CORPORATION OF CONNECTICUT.

WOOD-SCREW-MACHINE TOOL FEED.

Application filed January 3, 1922. Serial No. 526,495.

To all whom it may concern:

Be it known that I, HENRY L. SMITH, a citizen of the United States, residing at Waterbury, in the county of New Haven and State of Connecticut, have invented a new and useful Improvement in Wood-Screw-Machine Tool Feed, of which the following is a specification.

This invention relates to those machines which are designed to cut a plurality of threads on screw blanks. In automatic wood screw machines the thread cutting tools are fed and returned along each blank several times. At the end of each feed the cutting edges of the tools are turned out from the blank so that they may be returned for the next cut. After each return the cutting edges are turned in toward the axis of the blank slightly further than during the previous forward feed so as to increase the depth of the cuts. The feed and return movements are controlled by feed cams, the depths of the cuts are controlled by depth cams and the contours of the cuts 25 are controlled by profile cams.

The object of the present invention is to so design the tool controlling mechanism of a screw machine of this class which has two threading tools on the same side of the blank, that while both tools are fed by the same feed cam the threads cut will start on diametrically opposite sides of the blank at the same distance from the point.

To accomplish this with two tools arranged side by side on the same side of the blank and fed and returned together by the same means, in the embodiment of the invention illustrated two similar profile cams, one for each tool, and two similar depth cams, one for each profile cam, are arranged to co-operate in such manner that the following tool is not turned into cutting position until it has been fed longitudinally of the blank such a distance that it will begin to cut on the opposite side of the blank at the same distance from the point that the advance tool started cutting.

In the accompanying drawings Figure 1 shows a front elevation of so much of a wood screw machine as is necessary to an understanding of the present invention. Fig. 2 shows a vertical section of the mechanism taken on the plane indicated by the dotted line 2-2 on Fig. 3. Fig. 3 shows

a plan of the depth cams and profile cams 55 with their co-operating connections, which control the actions of the two tools.

In the machine illustrated the following tool 4 is clamped in a holder 5 that is fastened to a tubular shaft 6. The advance 60 tool 7 is clamped in a holder 8 that is fastened to a tubular shaft 9 which is fitted upon the shaft 6 so that the two shafts may be rotated independently but will move longitudinally as one. One end of the shaft 65 6 has a shoe 10 that is held in engagement with the feed cam 11 of common outline and which is rotated by the usual mechanism. In the interior of the shaft 6 is a spiral spring 12 which is arranged to thrust 70 between the shaft at a point near the feed cam and a rod 13 that extends into the other end of the shaft. The pressure of this spring holds the shaft shoe 10 yielding against the feed cam.

Fastened to the shaft 6 which carries the following tool is a rocker arm 14 that at its forward end has a shoe 15 which is held in engagement with the edge of the profile cam 16 by a spring 17. Fastened to the 80 shaft 9 which carries the advance tool is a rocker arm 18 that at its forward end has a shoe 19 which is held in engagement with the edge of a profile cam 20 by a spring 21. Through these parts the tools are turned 85 in toward and out from the screw blank independently, each controlled by its own profile cam, as the shaft is fed and returned by the common feed cam and spring. The profile cams which are similar are adjustably fastened to the fronts of similar yoke-shaped saddles 22 which are independently pivotally mounted in the frame 23 concentric with the shafts 6 and 9. Projecting rearwardly from the saddles are levers 24 95 the ends of which are successively engaged by the surfaces 25 of the cut cams 26 that are adjustably mounted on the cam shaft 27. The cut cams illustrated are alike and are of the type described in United States 100 Letters Patent #1,196,308 granted on my application August 29th, 1916. When the end of one of these levers is engaged by one of the cam surfaces the saddle to which the lever is attached is swung so as to rock the 105 feed shaft which is controlled by the profile cam carried by that saddle and turn the tool that is mounted on that shaft in to-

2

ward the screw blank. The parts are so timed that the ends of the levers drop into one of the spaces 28 and allow the tools to be drawn away from the screw blank as the return movement of the tools is being effected. Each succeeding projection of the cams is higher than the preceding projections in order that a deeper cut shall be made by the tools after each return movement, as set forth in the above mentioned patent. The cut cam which through its profile cam controls the following tool is adjusted slightly behind the cut cam which through its profile cam controls the advance tool so that the following tool will not be engaged with the blank for cutting until it has reached the locality opposite the point where the advance tool was turned up and began to cut. The cam shaft and feed cam illustrated may be driven by mechanism similar to that described in United States Letters Patent #1,170,694 granted on my application February 8th, 1916.

By the means described while one tool follows the other and both are fed by the same feed cam, the following tool does not begin its cut until it is the same distance from the point and diametrically opposite from where the advance tool began to cut the blank and as a result a screw is formed with two threads each of which starts the same distance from the point.

The invention claimed is:

1. A screw machine having a plurality of threading tools arranged side by side and mounted to move together longitudinally of the blank to be threaded, but move independently transversely of the blank, common means for feeding the tools together longitudinally of the blank, and independent means for feeding the tools transversely of the blank, said latter means acting to feed the advance tool transversely before feeding the following tool transversely, whereby the tools begin to cut at the same distance from the point of the blank but each cuts a separate thread.

2. A screw machine having a plurality of threading tools arranged side by side on the same side of the blank to be threaded, said

tools being mounted to move together longitudinally of the blank, but move independently transversely of the blank, and independent means for oscillating the advance tool transversely of the blank before oscillating the following tool transversely of the blank, whereby the tools begin to cut at the same distance from the point of the blank.

3. A screw machine having a plurality of threading tools arranged side by side on the same side of the blank to be threaded, a common cam for feeding both tools, independent cams for determining the depth of cuts of the tools, and independent cams for determining the profile of the cuts, said profile cams being independently oscillated by the depth cut cams for oscillating the tools.

4. A screw machine having a plurality of threading tools arranged side by side on the same side of the blank to be threaded, a common feed cam for feeding both tools longitudinally of the blank, a common spring for returning both tools together, independent cut cams for determining the depth of the cut of the tools, and independent profile cams each controlled by a cut cam for moving the tools toward and from the blank.

5. A screw machine having a plurality of threading tools arranged side by side on the same side of the blank to be threaded, a cam for feeding the tools longitudinally of the blank, cams for swinging the tools toward the axis of the blank, and cams controlling the position of the latter cams, said cams being so timed that the following tool does not begin to cut until it has reached the locality with relation to the point of the blank at which the advance tool began to cut.

6. A screw machine having a plurality of threading tools arranged side by side on the same side of the blank to be threaded, a single cam for feeding the tools longitudinally of the blank, and two independent profile cams and two independent cut cams for oscillating the tools independently toward and from the blank, said cams being adjusted to cause the advance tool to begin cutting before the following tool is allowed to cut.

HENRY L. SMITH.
